UNITED STATES PATENT OFFICE

HENRY J. KASCH, OF DAYTON, OHIO

DESIGN FOR A KNOB

Application filed August 12, 1929. Serial No. 32,390. Term of patent 14 years.

To all whom it may concern:

Be it known that I, HENRY J. KASCH, a citizen of the United States, residing at Dayton, Montgomery County, Ohio, have invented a new, original, and ornamental Design for a Knob, of which the following is a specification.

Fig. 1 is a front elevation of a knob embodying my new design. Fig. 2 is a perspective view thereof. Fig. 3 is a side elevation of a knob embodying my new design.

The dominant feature of the design comprises the stepped top of the knob embodying a succession of polygonal layers superposed one upon another in non-parallel relation.

I claim:

The ornamental design for a knob substantially as shown and described.

In testimony whereof, I have hereunto set my hand this 7th day of July, 1929.

HENRY J. KASCH
